FIG 1

FIG 4

FIG. 2

FIG. 3

FIGURE 1 is a front perspective view of an oil burner embodying our novel design.

FIG. 2 is a side elevation, taken from the right side of the oil burner as shown in FIG. 1.

FIG. 3 is a side elevation, taken from the left side of the oil burner as shown in FIG. 1.

FIG. 4 is a rear elevation on a somewhat reduced scale of the oil burner shown in the preceding figures.

The dominant features of our design reside in the portions shown in full lines, with the support base and arms shown in dotted lines in FIGS. 1, 2 and 3 for illustrative purposes only.

We claim:

The ornamental design for an oil burner, as shown and described.
